UNITED STATES PATENT OFFICE.

CHARLES M. GOODRICH, OF CLINTON, IOWA.

LOCOMOTIVE-CAB WINDOW.

No. 905,417.

Specification of Letters Patent.

Patented Dec. 1, 1908.

Application filed January 13, 1908. Serial No. 410,493.

To all whom it may concern:

Be it known that I, CHARLES M. GOODRICH, a citizen of the United States, residing at Clinton, county of Clinton, and State of Iowa, have invented certain new and useful Improvements in Locomotive-Cab Windows, of which the following is a specification.

My invention relates to locomotive cabs and particularly to the front window thereof on the engineer's side. As now arranged, these windows reflect the light from the furnace door when opened, which at night interferes with the engineer's view of the track, frequently resulting in serious accidents.

The object of my invention is to provide the cab on the right hand or engineer's side with a window so arranged that it will not reflect the lights from within or behind the cab into the engineer's face to obscure his vision.

A further object of my invention is to provide a device as mentioned which may be readily applied to any locomotive cab to replace the window now in use thereon.

Other objects will appear hereinafter.

With these objects in view my invention consists generally in a casing adapted to be secured to the front of a cab about the usual window opening and a window hingedly mounted therein and adapted to rest at an angle to the front of the cab when in closed position.

My invention further consists in various details of construction and arrangements of parts all as will be hereinafter fully described and particularly pointed out in the claims.

My invention will be more readily understood by reference to the accompanying drawings forming a part of this specification and in which,

Figure 1 is a horizontal sectional view through a locomotive cab window embodying my invention in its preferred form, Fig. 2 is a perspective view of the same from the outside showing the adjacent portion of the cab to which it is attached, and Fig. 3 is a perspective view from the inside illustrating the device detached from the cab.

The casing which is to be secured to the front of the cab comprises a side plate, 1 and the triangular top and bottom plates 2 and 3 respectively. These are preferably formed of one piece of iron and are pro-

vided with the flanges, 4, by which it is secured to the cab, the flanges being provided with screw or bolt holes, 5 for this purpose. The side plate, 1 is arranged at the outer or right hand side of the window and extends directly forwardly from the edge of the window opening, 6, that is, at right angles to the front wall of the cab. The top and bottom plates, 2 and 3 are arranged so that their outer edges extend from the outer edge of the plate, 1 to the edge of the window opening 65 on the opposite side terminating in the enlarged or extended portion, 7, the purpose of which will appear hereinafter. The plates, 1, 2 and 3, are provided with weather moldings, 8 arranged parallel with the outer edge 70 of their respective plate and against which the window sash abuts when in closed position, the moldings being arranged an equal distance from the edge of the plate as the thickness of the window, in order to bring 75 the outer face of the window when closed flush with the edges of the plates.

9 indicates the window sash hingedly connected as at 10 to the window frame, 11 of the window opening and on the side opposite the plate, 1. The sash thus sets at an angle to the front of the cab, inclined toward the boiler, the inner edge being flush with the cab front and the outer edge advanced forwardly the width of the plate 1. The 80 edges of the sash are beveled as at 12 and 13 to fit snugly against the plate 1 and the frame, 11 when in closed position, (see Fig. 1), and the inner corner of the sash is also beveled as at 14 in order to bring the corner 85 flush with the inner face of the frame, 11. The hinges, 10 are arranged between the portions, 7 of the bottom and top plates of the casing and these portions prevent anything from being caught between the edge 90 of the sash and said plates when the window is open.

15 indicates double plates of glass arranged in the sash with the air space 16 between them to prevent frost from accumulating 100 thereon.

By arranging the window at an angle to the front of the cab as shown, the engineer's view of the track is not interfered with to the slightest extent, and all lights from 105 within or behind the cab, which strike the window are reflected toward the plate, 1 instead of into the engineer's face. Further

it is obvious that the device may be readily attached to any locomotive cab now in use, and that at little cost.

Having described my invention what I claim as new and desire to secure by Letters Patent is:

1. In a locomotive, the cab having the usual front lookout window opening arranged to the right of the boiler, in combination with a sash hingedly connected to the side of said opening adjacent to the boiler and means for holding said sash at an angle to prevent reflection of lights into the engineer's face from within or behind said cab substantially as described. 10
2. In a locomotive, the cab having the usual front window opening, in combination with a window angularly arranged in said opening as and for the purpose specified. 20
3. In a locomotive, the cab having the usual front window opening, in combination with a casing arranged about said window opening and a window sash angularly arranged in said casing, substantially as described. 25
4. In a locomotive, the cab having the usual front window opening, in combination with a casing arranged about said window opening and comprising, a side plate and a triangular top and bottom plate formed integrally therewith and each provided with means for attaching the same to the cab and a window sash hingedly connected to the cab at the opposite side of the window opening from the plate and adapted to rest at an angle within said casing when in closed position, substantially as described. 30
5. In a locomotive, the cab having the usual front window opening, in combination with a casing arranged about said opening and comprising a side plate and a triangular top and bottom plate formed integrally therewith, each provided with means for attaching the same to the cab, a window sash hingedly connected to the frame of said window opening upon the opposite side from said side plate and adapted to swing outwardly and a molding arranged substantially parallel with the outer edges of the several plates of said casing to limit the in- 35
- ward movement of said sash and to hold the same at an angle within said casing, substantially as described. 40
6. In a locomotive, the cab having the usual front window opening, in combination with a casing arranged about said opening and comprising a side plate and a triangular top and bottom plate formed integrally therewith and each provided with a flange for attaching the same to the cab, a window sash hingedly connected with the frame of said window opening upon the opposite side from said plate and a molding arranged substantially parallel with the outer edges of the several plates to hold the sash at an angle, substantially as described. 55
7. In a locomotive, the cab having the usual front window opening in combination with a casing arranged about said opening and comprising a metal plate extending directly forward from the right-hand edge of said opening and a triangular top and bottom plate each provided with means for attaching the same to the cab and a sash hingedly connected to the frame of said opening upon the opposite side from said plate and adapted to rest in the outer end of said casing and at an angle to the front of the cab substantially as described. 60
8. In a locomotive, the cab having the usual front window opening in combination with a casing arranged about said opening and comprising a side plate extending forwardly from one edge of said opening and a triangular top and bottom plate each provided with means for attaching the same to the cab and a sash hingedly connected to the frame of said opening upon the opposite side from said plate, and said triangular plates having extensions arranged directly above and below the hinged edge of said sash substantially as described. 65
9. In testimony whereof I have signed my name to this specification in the presence of two subscribing witnesses. 70

CHARLES M. GOODRICH.
